UNITED STATES PATENT OFFICE.

EDWARD CRAIG, OF ST. JOSEPH, MICHIGAN, ASSIGNOR TO SARANAC MACHINE CO., OF ST. JOSEPH, MICHIGAN, A CORPORATION OF MICHIGAN.

BASKET-COVER MACHINE.

1,177,587.

Specification of Letters Patent. Patented Mar. 28, 1916.

Application filed November 29, 1909. Serial No. 530,648.

To all whom it may concern:

Be it known that I, EDWARD CRAIG, a citizen of the United States of America, and resident of St. Joseph, Berrien county, 5 Michigan, have invented a certain new and useful Improvement in Basket-Cover Machines, of which the following is a specification.

My invention relates to machinery for 10 making articles on forms.

As herein disclosed, my invention takes the form of a machine for basket covers, such as are used on bushel baskets. It may take other forms for other purposes.

15 My invention contemplates an improved construction and arrangement in a plurality of rotary forms which are also bodily movable about a common axis to bring them successively into coöperation with a stapler or 20 other fastener applying mechanism.

It also contemplates certain other novel features and combinations tending to increase the efficiency of a machine of this particular character.

25 The object of my invention, generally stated, is to increase the speed of production and thereby decrease the cost of manufacture of basket covers or any other articles that can be made on a machine embodying the principles of my invention.

In the accompanying drawings, Figure 1 is a side elevation of a basket cover machine constructed in accordance with my invention. Fig. 2 is a plan of the said machine. Fig. 3 is a horizontal section on line 3—3 in Fig. 1. Fig. 4 is a vertical section on line 4—4 in Fig. 2. Fig. 5 is a plan of a basket cover, showing the manner in which the slats thereof are held in position by pins 40 and brackets on the tops of the forms. Fig. 6 is a vertical section on line 6—6 in Fig. 1. Fig. 7 is a fragmentary perspective of a portion of one of the forms, showing the cam that operates the trip to automatically 45 stop the machine when the cover is finished. Fig. 8 is a perspective of one of the hoop clamps with which the forms are provided. Fig. 9 is an enlarged vertical section on line 9—9 in Fig. 3. Fig. 10 is a horizontal 50 section on line 10—10 in Fig. 1. Fig. 11 is an enlarged plan view of the hinged portion of the feed pawl. Fig. 12 is a side elevation of the parts shown in Fig. 11.

As thus illustrated, the operative parts

are suitably supported upon an upright support or pedestal A, which has a base *a* adapted to rest on the floor. The drive shaft B is disposed horizontally at the bottom of said pedestal A, and has a clutch *b* controlling the communication of power thereto from the pulley *b'*. This shaft has a crank connection *b*² for operating the rod *b*³ that operates the stapler head C.

The stapler mechanism may be of any suitable character, but is preferably provided with a cam lever *c* that engages the upper end of the staple driver *c'*. This lever is pivoted on the head C and held by a spring *c*² against the thrust of the driver. In this way the driver can yield if it strikes the work before the head stops moving downward. Another novel feature of the stapler is the spring break *c*³ for the wire feed wheel *c*⁴. This spring is applied to the side of the wheel, and its tension is adjustable by means of the thumb screw or nut *c*⁵. This prevents overfeeding—that is, prevents the feed wheel from rotating by momentum. The stapler is otherwise of any suitable, known or approved form.

The form carrier D is pivoted at *d* upon the pedestal and arranged to swing back and forth below the said stapler. It has adjustable stops *d'* that engage the pedestal to limit the swing. The rotary forms E and E' are mounted at *e* and *e'* upon the said carrier. Each form has a ring *e*² adapted to receive the hoop of the basket cover, and is also provided with four clamps *e*³ that serve to clamp the said hoop against the said ring—that is, the clamps engage the inside of the hoop. These clamps are operated by links *e*⁴ connected to a head or spider *e*⁵, which latter is operated vertically by a rod *e*⁶. The up and down motion of the head *e*⁵ moves the clamps *e*³ radially. Each form has a suitably mounted lever *e*⁷ for operating the rod *e*⁶. There is also a friction brake *e*⁸ for each form, which prevents over-feeding. Each form has circumferential teeth *e*⁹, and a circumferential cam *e*¹⁰, see Fig. 7. The parallel slats X of the cover are spaced apart by the pins *e*¹¹ on the forms. The one cross slat Z is held in place by U-shaped brackets or lugs *e*¹² on the top of each form. Each clamp *e*³ has a shank *e*¹³ that slides in a guide *e*¹⁴ on the top of the form.

The feed mechanism consists of a feed pawl F connected with a bell crank lever f. This pawl has a joint f' about which it may swing vertically, and another joint f² about which it may swing horizontally. It is held against horizontal displacement, yieldingly, by springs f³ that bear at each side thereof. A spring f⁴ serves to hold the pawl down in place upon the plate or carrier D. In this way the pawl can act on the teeth e⁰ of the form. For this purpose said pawl has two engaging prongs or portions f⁵, one prong being allotted to one form, and the other prong being for the other form, and the teeth of one form face in the same direction as those of the other form. One spring f³ is allotted to one prong f⁵, and the other spring is for the other prong, as these prongs must be held yieldingly in opposite directions. Thus the forms rotate in opposite directions, the feeding motion alternating with the operation of the stapler. A handle d² is provided for moving the plate D to swing the forms back and forth. This enables the operator to make the forms change places. In other words, the forms are brought successively into coöperation with the stapler. While one form is being loaded, the other form is having the materials thereon stapled together by the stapler. One cover is being formed while the preceding one is being stapled together.

During the stapling operation the plate or carrier D is held locked by the locking pin G which is adapted to engage the holes g in said plate. The pin G is on a lever g' that is operated by the trip rod g², which latter connects with the foot lever g³. This foot lever or treadle controls the clutch b' that starts and stops the machine. A spring g⁴ tends to lift the lever g³. A lever g⁵ is pivoted at g⁶ on the bracket g⁷ on the pedestal, and provided with cam portions g⁸ adapted to alternately engage the cam notch g⁹ in the rod g². The springs g¹⁰ serve to draw the lever g⁵ into a central position, to move the end of the said lever over the top of the rod g², so that the latter cannot rise when the foot is taken off the lever g³. As shown the machine is ready to start, and when the foot lever is depressed, the cam g⁹ engages the cam g⁸ at one side of the lever g⁵, and then the end of said lever g⁵ moves over the top of the rod g², and the pin G engages one of the holes g to lock the forms against swinging movement during operation of the stapler. When the form in operation completes its rotation the cam e¹⁰ strikes the roll g¹¹ on the lever g⁵ and thereby moves the latter sufficiently to release the rod g², which stops the machine. By the handle g¹² on the said lever g⁵ the machine can be stopped at any time. When the machine is stopped the pin G is disengaged from the plate D, to unlock the latter, so

that it can be shifted to bring the other form into operation.

Any suitable means can be employed for operating the lever f. As shown, the lever is connected by a bar or rod H with the roll h, which latter is suitably mounted to move up and down on the lever h'. A cam h² on the shaft B engages the roll h to move the rod H up and down and thereby operate the feed mechanism. A spring h³ serves to 75 keep the roll h in firm engagement at all times with the cam h². Thus the feed mechanism for rotating the forms E and E' is operated from the main drive shaft. By swinging the forms from side to side a single 80 feed pawl is sufficient for both forms. This permits the stapler to be stationary, which renders the machine strong and less liable to work loose. The staples will, therefore, always be driven correctly in the covers. 85

I do not limit myself to the exact construction, or to the use of my invention for any particular purpose. It may be used for making various articles.

What I claim as my invention is:

1. In a machine of the class described, a plurality of forms arranged for operation one at a time only, each form rotatable about an axis, whereby one form may remain stationary, a common axis for said forms, means for moving said forms bodily about said common axis, and mechanism having a fixed position for applying fastening means to the work on said forms, said forms movable in unison to bring them successively 100 into coöperation with said mechanism, and the operating position of one form being different from that of another form. 95

2: In a machine of the class described, a plurality of rotary forms arranged for operation one at a time only, means for rotating the forms in succession, about axes which are stationary during such rotation, whereby one form may remain stationary, means for moving each form bodily, and means coöperating with said forms to complete the work, said axes having non-coincident operating positions. 110

3. In a machine of the class described, a plurality of rotary forms arranged for operation one at a time only, means for rotating the forms in succession, about axes which are stationary during such rotation, whereby one form may remain stationary, means including a shifting support for moving the forms bodily about a common axis, and stops so arranged that the axis of one form assumes a position previously occupied by the axis of the other form. 115

4. In a machine of the class described, a plurality of forms arranged for operation one at a time only, each form rotatable about an axis of its own, while such axis is stationary, whereby one form may remain stationary, a stapler, and means including a 120

shifting support for bringing said forms successively into coöperation with said stapler, each form having a plurality of recurring positions, relative to said stapler, 5 and all positions of one form being different from those of the other.

5. In a machine of the class described, a plurality of forms arranged for operation one at a time only, each rotatable about a 10 vertical axis, while such axis is stationary, whereby one form may remain stationary, a stapler, means operating in alternation with the stapler to rotate the forms, said means having a different operating position 15 for each form, and means including a shifting support for bringing said forms successively into coöperation with said stapler.

6. In a machine of the class described, a 20 plurality of rotary forms arranged for operation one at a time only, a feed mechanism for rotating said forms, about axes which are stationary during such rotation, whereby one form may remain stationary, and 25 means whereby said forms are each shifted and thereby operated successively and in different directions by said mechanism.

7. In a machine of the class described, a 30 plurality of rotary forms arranged for operation one at a time only, means for rotating said forms in succession in different directions, about axes that are stationary during such rotation, whereby one form may remain stationary, a stapler, and means including 35 a shifting support whereby said forms are successively brought into coöperation with said stapler.

8. In a machine of the class described, a 40 plurality of rotary forms arranged for operation one at a time only, means for rotating said forms in succession in opposite directions, whereby one form may remain stationary, and means movably mounted for moving the forms bodily.

45 9. In a machine of the class described, a plurality of rotary forms arranged for operation one at a time only, teeth or projections for said forms, a single feed pawl for engaging said teeth or projections to 50 rotate the forms in succession, having a different operating position for each form, and means including a swinging support for permitting the moving of the forms successively into position to be operated by said pawl, whereby one form may remain stationary.

55 10. In a machine of the class described, a plurality of forms arranged for operation one at a time only, means for rotating said forms in succession, whereby one form may remain stationary, means including a swinging support for moving the forms bodily, means for locking the forms against bodily movement, means for automatically starting 60 the machine by the operation involving such

locking action, and means controlled by the forms for automatically stopping the machine whenever a form completes its rotation.

11. In a machine of the class described, 70 a plurality of forms arranged for operation one at a time only, each form rotatable about an independent axis, whereby one form may remain stationary, a common axis for said forms, said forms being movable bodily 75 about said common axis, and mechanism having a fixed position for applying fastening means to the work on said forms, said forms movable in unison to bring them successively into coöperation with said mechanism, a foot lever and means coöperating therewith to control at will actuation of the machine and to unlock or lock the forms against bodily movement.

12. In a machine of the class described, 80 a plurality of rotary forms arranged for operation one at a time only, means for rotating the forms in succession, about independent axes which are stationary during such rotation, whereby one form may remain stationary, and means including a shifting support for causing the forms to partially change places, a foot lever and means coöperating therewith to control at will actuation of the machine and to unlock or 90 lock the forms against bodily movement.

13. In a machine of the class described, a plurality of rotary forms arranged for operation one at a time only, means for rotating the forms in succession, about independent axes which are stationary during such rotation, whereby one form may remain stationary, means for moving each form bodily, and means coöperating with said forms to complete the work, a foot lever and 100 means coöperating therewith to control at will actuation of the machine and to unlock or lock the forms against bodily movement.

14. In a machine of the class described, 105 a plurality of rotary forms arranged for operation one at a time only, means for rotating the forms in succession, about independent axes which are stationary during such rotation, whereby one form may remain stationary, and means including a shifting support for moving the forms bodily about a common axis, a foot lever and means coöperating therewith to control at will actuation of the machine and to unlock or lock 110 the forms against bodily movement.

15. In a machine of the class described, a 115 plurality of forms arranged for operation one at a time only, each form rotatable about an independent axis of its own, while such axis is stationary, whereby one form may remain stationary, a stapler, and means including a shifting support for bringing said forms successively into coöperation with said stapler, a foot lever and means coöperating therewith to control at 125 120 the machine by the operation involving such

will actuation of the machine and to unlock or lock the forms against bodily movement.

16. In a machine of the class described, a plurality of forms arranged for operation one at a time only, each rotatable about a vertical axis, while such axis is stationary, whereby one form may remain stationary, a stapler, means operating in alternation with the stapler to rotate the form in stapling position, and means including a shifting support for bringing said forms successively into coöperation with said stapler, a foot lever and means coöperating therewith to control at will actuation of the machine and to unlock or lock the forms against bodily movement.
17. In a machine of the class described, a plurality of forms arranged for operation one at a time only, each rotatable about a vertical axis, whereby one form may remain stationary, a vertically disposed stapler arranged to work up and down above the said forms, means for rotating the forms in succession, and means including a shifting support for bringing said forms successively below said stapler, a foot lever and means coöperating therewith to control at will actuation of the machine and to unlock or lock the forms against bodily movement.
18. In a machine of the class described, a plurality of rotary forms arranged for operation one at a time only, a feed mechanism for rotating said forms in succession, about independent axes which are stationary during such rotation, whereby one form may remain stationary, and means whereby said forms are each shifted and thereby operated successively by said mechanism, a foot lever and means coöperating therewith to control at will actuation of the machine and to unlock or lock the forms against bodily movement.
19. In a machine of the class described, a plurality of rotary forms arranged for operation one at a time only, means for rotating said forms in succession in different directions, about independent axes that are stationary during such rotation, whereby one form may remain stationary, a stapler, and means including a shifting support whereby said forms are successively brought into coöperation with said stapler, a foot lever and means coöperating therewith to control at will actuation of the machine and to unlock or lock the forms against bodily movement.
20. In a machine of the class described, a plurality of rotary forms arranged for operation one at a time only, means for rotating said forms in succession in opposite directions, whereby one form may remain stationary, and means movably mounted for moving the forms bodily, a foot lever and means coöperating therewith to control at will actuation of the machine and to un-

lock or lock the forms against bodily movement.

21. In a machine of the class described, a plurality of rotary forms arranged for operation one at a time only, teeth or projections for said forms, a single feed pawl for engaging said teeth or projections to rotate the form in stapling position having a different operating position for each form, and means including a swinging support for permitting the moving of the forms successively into position to be operated by said pawl, whereby one form may remain stationary, a foot lever and means coöperating therewith to control at will actuation of the machine and to unlock or lock the forms against bodily movement.

22. In a machine of the class described, a plurality of forms arranged for operation one at a time only, means for rotating said forms, one after the other, whereby one form may remain stationary, means including a swinging support for permitting the moving of the forms bodily, means for locking the forms against bodily movement, means for automatically starting the machine by the operation involving such locking action, and means controlled by the forms for automatically stopping the machine whenever a form completes its rotation, a foot lever and means coöperating therewith to control at will the actuation of the machine and the locking of the forms against bodily movement.

23. In a machine of the class described, a plurality of forms arranged for operation one at a time only, each form rotatable about an axis, whereby one form may remain stationary, a common axis for said forms, said forms being movable bodily about said common axis, and mechanism having a fixed position for applying fastening means to the work on said forms, said forms movable in unison to bring them successively into coöperation with said mechanism, in combination with adjusting means serving in effect to regulate the bodily movement of said forms.

24. In a machine of the class described, a plurality of rotary forms arranged for operation one at a time only, means for rotating the forms in succession, about axes which are stationary during such rotation, whereby one form may remain stationary, and means including a shifting support for causing the forms to partially change places, in combination with adjusting means serving in effect to regulate the bodily movement of said forms.

25. In a machine of the class described, a plurality of rotary forms arranged for operation one at a time only, means for rotating the forms in succession, about axes which are stationary during such rotation, whereby one form may remain stationary,

means for moving each form bodily, and means coöperating with said forms to complete the work, in combination with adjusting means serving in effect to regulate the bodily movement of said forms.

26. In a machine of the class described, a plurality of rotary forms arranged for operation one at a time only, means for rotating the forms in succession, about axes which are stationary during such rotation, whereby one form may remain stationary, and means including a shifting support for moving the forms bodily about a common axis, in combination with adjusting means serving in effect to regulate the bodily movement of said forms.

27. In a machine of the class described, a plurality of forms arranged for operation one at a time only, each form rotatable about an axis of its own, while such axis is stationary, whereby one form may remain stationary, a stapler, and means including a shifting support for bringing said forms successively into coöperation with said stapler, in combination with adjusting means serving in effect to regulate the bodily movement of said forms.

28. In a machine of the class described, a plurality of forms arranged for operation one at a time only, each rotatable about a vertical axis, while such axis is stationary, whereby one form may remain stationary, a stapler, means operating in alternation with the stapler to rotate the form in stapling position, and means including a shifting support for bringing said forms successively into coöperation with said stapler, in combination with adjusting means serving in effect to regulate the bodily movement of said forms.

29. In a machine of the class described, a plurality of forms arranged for operation one at a time only, each rotatable about a vertical axis, whereby one form may remain stationary, a vertically disposed stapler arranged to work up and down above the said forms, means for rotating the forms in succession, and means including a shifting support for bringing said forms successively below said stapler, in combination with adjusting means serving in effect to regulate bodily the movement of said forms.

30. In a machine of the class described, a plurality of rotary forms arranged for operation one at a time only, a feed mechanism for rotating said forms in succession, about axes which are stationary during such rotation, whereby one form may remain stationary, and means whereby said forms are each shifted and thereby operated successively by said mechanism, in combination with adjusting means serving in effect to regulate the bodily movement of said forms.

31. In a machine of the class described, a plurality of rotary forms arranged for oper-

ation one at a time only, means for rotating said forms in succession in different directions, about axes that are stationary during such rotation, whereby one form may remain stationary, a stapler, and means including a shifting support whereby said forms are successively brought into coöperation with said stapler, in combination with adjusting means serving in effect to regulate the bodily movement of said forms.

32. In a machine of the class described, a plurality of rotary forms arranged for operation one at a time only, means for rotating said forms in succession in opposite directions, whereby one form may remain stationary, and means movably mounted for moving the forms bodily, in combination with adjusting means serving in effect to regulate the bodily movement of said forms.

33. In a machine of the class described, a plurality of rotary forms arranged for operation one at a time only, teeth or projections for said forms, a single feed pawl for engaging said teeth or projections to rotate the form in stapling position, having a different operating position for each form, and means including a swinging support for causing the forms to move successively into position to be operated by said pawl, whereby one form may remain stationary, in combination with adjusting means serving in effect to regulate the bodily movement of said forms.

34. In a machine of the class described, a plurality of forms arranged for operation one at a time only, means for rotating said forms in succession whereby one form may remain stationary, means including a swinging support for permitting the moving of the forms bodily, means for locking the forms against bodily movement, means for automatically starting the machine by the operation involving such locking action, and means controlled by the forms for automatically stopping the machine whenever a form completes its rotation, in combination with adjusting means serving in effect to regulate the bodily movement of said forms.

35. In a machine of the class described, a plurality of forms arranged for operation one at a time only, each form rotatable about an axis, whereby one form may remain stationary, a common axis for said forms, said forms being movable bodily about said common axis, and mechanism having a fixed position for applying fastening means to the work on said forms, said forms movable in unison to bring them successively into coöperation with said mechanism, each form being free to rotate in either direction when not in operation, and said forms having each an operative position different from that of the other.

36. In a machine of the class described, a plurality of rotary forms arranged for operation one at a time only, means for rotating

- the forms in succession, about axes which are stationary during such rotation, whereby one form may remain stationary, and means including a shifting support for causing 5 the forms to partially change places, each form being free to rotate in either direction when not in operation, and said forms having each an operative position different from that of the other.
- 10 37. In a machine of the class described, a plurality of rotary forms arranged for operation one at a time only, means for rotating the forms in succession, about axes which are stationary during such rotation, whereby 15 one form may remain stationary, means for moving each form bodily, and means co-operating with said forms to complete the work, each form being free to rotate in either direction when not in operation, and 20 said forms having each an operative position different from that of the other.
38. In a machine of the class described, a plurality of rotary forms arranged for operation one at a time only, means for rotating 25 the forms in succession, about axes which are stationary during such rotation, whereby one form may remain stationary, and means including a shifting support for moving the forms bodily about a common axis, each 30 form being free to rotate in either direction when not in operation, and said forms having each an operative position different from that of the other.
39. In a machine of the class described, a 35 plurality of forms arranged for operation one at a time only, each form rotatable about an axis of its own, while such axis is stationary, a stapler, and means including a shifting support for bringing said forms 40 successively into co-operation with said stapler, each form being free to rotate in either direction when not in operation, and said forms having each an operative position different from that of the other.
- 45 40. In a machine of the class described, a plurality of forms arranged for operation one at a time only, each rotatable about a vertical axis, while such axis is stationary, whereby one form may remain stationary, 50 a stapler, means operating in alternation with the stapler to rotate the form in stapling position, and means including a shifting support for bringing said forms successively into co-operation with said 55 stapler, each form being free to rotate in either direction when not in operation, and said forms having each an operative position different from that of the other.
41. In a machine of the class described, a 60 plurality of forms arranged for operation one at a time only, each rotatable about a vertical axis, whereby one form may remain stationary, a vertically disposed stapler arranged to work up and down above the said

forms, means for rotating the forms in succession, and means including a shifting support for bringing said forms successively below said stapler, each form being free to 65 rotate in either direction when not in operation, and said forms having each an operative 70 position different from that of the other.

42. In a machine of the class described, a plurality of rotary forms arranged for operation one at a time only, a feed mechanism for rotating said forms in succession, one at a time, about an axis which is stationary during such rotation, whereby one form may remain stationary, and means whereby said forms are each shifted and thereby operated successively by said mechanism, each form being free to rotate in either direction when not in operation, and said forms having each an operative position 80 different from that of the other.

43. In a machine of the class described, a plurality of rotary forms arranged for operation one at a time only, means for rotating said forms in succession in different directions, about axes that are stationary during such rotation, whereby one form may remain stationary, a stapler, and means including a shifting support whereby said forms are successively brought into co-operation with said stapler, each form being 90 free to rotate in either direction when not in operation, and said forms having each 95 an operative position different from that of the other.

44. In a machine of the class described, a 100 plurality of rotary forms arranged for operation one at a time only, means for rotating said forms in succession in opposite directions, whereby one form may remain stationary, and means movably mounted for 105 moving the forms bodily, each form being free to rotate in either direction when not in operation, and said forms having each an operative position different from that of the other.

45. In a machine of the class described, a plurality of rotary forms arranged for operation one at a time only, teeth or projections for said forms, a single feed pawl for engaging said teeth or projections to rotate 115 the form in stapling position, having a different operating position for each form, and means including a swinging support for causing the forms to move successively into position to be operated by said pawl, whereby one form may remain stationary, each form being free to rotate in either direction 120 when not in operation, and said forms having each an operative position different from that of the other.

46. In a machine of the class described, a plurality of forms arranged for operation one at a time only, means for rotating said

- forms in succession, whereby one form may remain stationary, means including a swinging support for moving the forms bodily, means for locking the forms against bodily movement, means for automatically starting the machine by the operation involving such locking action, and means controlled by the forms for automatically stopping the machine whenever a form completes its rotation, each form being free to rotate in either direction when not in operation, and said forms having each an operative position different from that of the other. 65
47. In a machine of the class described, a plurality of forms arranged for operation one at a time only, each form rotatable about an axis, whereby one form may remain stationary, a common axis for said forms, said forms being movable bodily about said common axis, mechanism having a fixed position for applying fastening means to the work on said forms, said forms movable in unison to bring them successively into coöperation with said mechanism, a rotary work clamp for each form, movable bodily therewith, and a lever for each clamp. 70
48. In a machine of the class described, a plurality of rotary forms arranged for operation one at a time only, means for rotating the forms in succession, about axes which are stationary during such rotation, whereby one form may remain stationary, means including a shifting support for causing the forms to partially change places, a rotary work clamp for each form, movable bodily therewith, and a lever for each clamp. 75
49. In a machine of the class described, a plurality of rotary forms arranged for operation one at a time only, means for rotating the forms in succession, about axes which are stationary during such rotation, whereby one form may remain stationary, means for moving each form bodily, means coöperating with said forms to complete the work, a rotary work clamp for each form, movable bodily therewith, and a lever for each clamp. 80
50. In a machine of the class described, a plurality of rotary forms arranged for operation one at a time only, means for rotating the forms in succession, about axes which are stationary during such rotation, whereby one form may remain stationary, means including a shifting support for moving the forms bodily about a common axis, a rotary work clamp for each form, movable bodily therewith, and a lever for each clamp. 85
51. In a machine of the class described, a plurality of forms arranged for operation one at a time only, each form rotatable about an axis of its own, while such axis is stationary, whereby one form may remain stationary, a stapler, means including a shifting support for bringing said forms successively into coöperation with said stapler, a rotary work clamp for each form, movable bodily therewith, and a lever for each clamp. 90
52. In a machine of the class described, a plurality of forms arranged for operation one at a time only, each rotatable about a vertical axis, while such axis is stationary, whereby one form may remain stationary, a stapler, means operating in alternation with the stapler to rotate the form in stapling position, means including a shifting support for bringing said forms successively into coöperation with said stapler, a rotary work clamp for each form, movable bodily therewith, and a lever for each clamp. 95
53. In a machine of the class described, a plurality of forms arranged for operation one at a time only, each rotatable about a vertical axis, whereby one form may remain stationary, a vertically disposed stapler arranged to work up and down above the said forms, means for rotating the forms in succession, means including a shifting support for bringing said forms successively below said stapler, a rotary work clamp for each form, movable bodily therewith, and a lever for each clamp. 100
54. In a machine of the class described, a plurality of rotary forms arranged for operation one at a time only, a feed mechanism for rotating said forms in succession, one at a time, about axes which are stationary during such rotation, whereby one form may remain stationary, means whereby said forms are each shifted and thereby operated successively by said mechanism, a rotary work clamp for each form, movable bodily therewith, and a lever for each clamp. 105
55. In a machine of the class described, a plurality of rotary forms arranged for operation one at a time only, means for rotating said forms in succession in different directions, about axes that are stationary during such rotation, whereby one form may remain stationary, a stapler, means including a shifting support whereby said forms are successively brought into coöperation with said stapler, a rotary work clamp for each form, movable bodily therewith, and a lever for each clamp. 110
56. In a machine of the class described, a plurality of rotary forms arranged for operation one at a time only, means for rotating said forms in succession in opposite directions, whereby one form may remain stationary, means movably mounted for moving the forms bodily, a rotary work clamp for each form, movable bodily therewith, and a lever for each clamp. 115
57. In a machine of the class described, a plurality of rotary forms arranged for operation one at a time only, teeth or projections for said forms, a single feed pawl for engaging said teeth or projections to rotate the form in stapling position, having a dif- 120
- 125

ferent operating position for each form, means including a swinging support for causing the forms to move successively into position to be operated by said pawl, whereby one form may remain stationary, a rotary work clamp for each form, movable bodily therewith, and a lever for each clamp.

58. In a machine of the class described, a plurality of forms arranged for operation 10 one at a time only, means for rotating said forms in succession, whereby one form may remain stationary, means including a swinging support for moving the forms bodily, means for locking the forms against bodily 15 movement, means for automatically starting the machine by the operation involving such locking action, means controlled by the forms for automatically stopping the machine whenever a form completes its rotation, a rotary work clamp for each form, movable bodily therewith, and a lever for each clamp.

59. In a machine of the class described, a plurality of forms arranged for operation 25 one at a time only, each form rotatable about an axis, whereby one form may remain stationary, a common axis for said forms, said forms being movable bodily about said common axis, and mechanism having a fixed position for applying fastening means to the work on said forms, said forms movable in unison to bring them successively into co-operation with said mechanism, said forms having each a loading position different 30 from that of the other.

60. In a machine of the class described, a plurality of rotary forms arranged for operation one at a time only, means for rotating the forms in succession, about axes 0 which are stationary during such rotation, whereby one form may remain stationary, and means including a shifting support for causing the forms to partially change places, said forms having each a loading position 5 different from that of the other.

61. In a machine of the class described, a plurality of rotary forms arranged for operation one at a time only, means for rotating the forms in succession, about axes which are stationary during such rotation, whereby one form may remain stationary, means for moving each form bodily, and means co-operating with said forms to complete the work, said forms having each a loading position different from that of the other.

62. In a machine of the class described, a plurality of rotary forms arranged for operation one at a time only, means for rotating the forms in succession, about axes which are stationary during such rotation, whereby one form may remain stationary, and means including a shifting support for moving the forms bodily about a common axis, said forms having each a loading position different from that of the other.

63. In a machine of the class described, a plurality of forms arranged for operation one at a time only, each form rotatable about an axis of its own, while such axis is stationary, whereby one form may remain stationary, a stapler, and means including a shifting support for bringing said forms successively into co-operation with said stapler, said forms having each a loading position different from that of the other. 70

64. In a machine of the class described, a plurality of forms arranged for operation one at a time only, each rotatable about a vertical axis, whereby one form may remain stationary, a vertically disposed stapler arranged to work up and down above the said forms, means for rotating the forms in succession, and means including a shifting support for bringing said forms successively below said stapler, said forms having each a 80 loading position different from that of the other.

65. In a machine of the class described, a plurality of rotary forms arranged for operation one at a time, only, a feed mechanism for rotating said forms in succession, one at a time, about an axis which is stationary during such rotation, whereby one form may remain stationary, and means whereby said forms are each shifted bodily 90 and thereby brought into position to be operated successively by said mechanism, said forms having each a loading position different from that of the other. 95

66. In a machine of the class described, a plurality of rotary forms arranged for operation one at a time only, means for rotating said forms in succession in different directions, about axes that are stationary during such rotation, whereby one form may remain stationary, a stapler, and means including a shifting support whereby said forms are successively brought into co-operation with said stapler, said forms having each a loading position different from that of the other. 100

67. In a machine of the class described, a plurality of rotary forms arranged for operation one at a time only, means for rotating said forms in succession in opposite directions, whereby one form may remain stationary, and means movably mounted for moving the forms bodily, said forms having each a loading position different from that of the other. 115

68. In a machine of the class described, a plurality of rotary forms arranged for operation one at a time only, teeth or projections for said forms, a single feed pawl for engaging said teeth or projections to rotate the form in stapling position, having a different operating position for each form, and means including a swinging support for permitting the moving of the forms successively into position to be operated by said pawl, 125 130

whereby one form may remain stationary, said forms having each a loading position different from that of the other.

69. In a machine of the class described, a plurality of forms arranged for operation one at a time only, means for rotating said forms in succession, whereby one form may remain stationary, means including a swinging support for moving the forms bodily, 10 means for locking the forms against bodily movement, means for automatically starting the machine by the operation involving such locking action, and means controlled by the forms for automatically stopping the 15 machine whenever a form completes its rotation, said forms having each a loading position different from that of the other.
70. In a machine of the class described, a plurality of forms arranged for operation 20 one at a time only, each rotatable about a vertical axis, which such axis is stationary, whereby one form may remain stationary, a stapler, means operating in alternation with the stapler to rotate the form in 25 stapling position, and means including a shifting support for bringing said forms suc-

cessively into coöperation with said stapler, said forms having each a loading position different from that of the other.

71. In a machine of the class described, a 30 pair of rotary forms, each form having ratchet teeth, and a two pronged pawl for alternately rotating said forms, one of said prongs engaging the teeth on one form, and the other prong engaging the teeth on the 35 other form.

72. In a machine of the class described, a 40 pair of rotary forms, each form having ratchet teeth, and a two pronged pawl for alternately rotating said forms, one of said prongs engaging the teeth on one form, and the other prong engaging the teeth on the other form, means for shifting the position of said forms, and springs for said pawl, each spring being allotted to one of said 45 prongs.

Signed by me at St. Joseph, Michigan,
this 19 day of November 1909.

EDWARD CRAIG.
